GRINDING COMPANY, OF WORCESTER, MASSACHUSETTS, A CORPORATION OF
MASSACHUSETTS.

REVERSING MECHANISM.

1,191,987.

Specification of Letters Patent. Patented July 25, 1916.

Application filed November 5, 1915. Serial No. 59,855.

To all whom it may concern:

Be it known that I, CHARLES H. NORTON, a citizen of the United States, residing at Worcester, in the county of Worcester and 5 State of Massachusetts, have invented a new and useful Reversing Mechanism, of which the following is a specification.

This invention relates to a reversing mechanism of general application but more particularly designed for use in reversing the 10 work table of a modern high duty grinding machine.

The work table in a modern grinding machine is often of large size and great weight 15 and it is moved at a rate of speed which renders the reversal of its travel a very serious problem. The reversal period is necessarily very short and the shock and strain of the reversal is severe. In fact the 20 permissible reversal strain practically determined the maximum table speed in many grinding machines.

It is the general object of my invention to provide an improved reversing mechanism 25 by means of which a heavy moving work table or other similar object may have its direction of travel at high speed reversed without shock or undue strain upon the driving or reversing mechanism.

With this general object in view one feature of my invention relates to the provision 30 of mechanism for effectively reversing a worm and worm wheel drive, the worm at the moment of reversal being given a sliding 35 instead of an angular movement. In the preferred form, the worm is free to move both axially and angularly upon its driving shaft, suitable provision being made for limiting both the axial and angular movement.

More specifically my invention relates to the provision, in a worm and worm wheel drive, of a sliding worm having a cam disk secured to each end thereof and coöperating 45 with rolls carried by a pair of driving arms fixed to the shaft upon which the worm is supported.

Further features of my invention relate to the provision of means for yieldingly retaining the cam disks and driving arms in 50 operative relation while the table is being brought to rest and to the provision of special constructions in the cam disks for preventing shock to the mechanism during this 55 retarding action.

My invention also relates to certain arrangements and combinations of parts which will be hereinafter described and more particularly pointed out in the appended claims.

Preferred forms of my invention are 60 shown in the drawings, in which—

Figure 1 is a front elevation of my improved reversing mechanism; Fig. 2 is an enlarged sectional elevation taken through the axis of the driving shaft and showing 65 the driving connections between the shaft and the worm; Fig. 3 is a diagrammatic plan view showing the relations of the cam disks to each other; Fig. 4 is a development 70 of one of the cams; Fig. 5 is a development of a modified form of cam, and Fig. 6 is a sectional elevation of a modified form of my invention.

Referring to the drawings, I have shown my improved reversing mechanism as embodied 75 in the table drive of a grinding or other similar machine.

The work table is indicated at 10 and is provided with a rack 11 meshing with a pinion 12 fixed to a shaft 13 driven by a 80 worm wheel 14. The worm wheel 14 is driven by a worm 15 mounted upon a driving shaft 16 rotatable in bearings 17 and 18 carried by a frame 19. These bearings are preferably of the ball bearing type (as indicated in Fig. 2) and are designed to resist both the radial and the axial thrust of the driving shaft.

For the purposes of this application the driving shaft may be considered as revolving in fixed bearings and as being restrained from axial movement in said bearings. Under certain conditions it may be desirable to provide for a slight axial cushioning movement of the shaft, but such provision would not modify or in any way interfere with the operation of the mechanism herein shown. Any suitable mechanism may be provided for driving the shaft 16 alternately in opposite directions. In 100 Fig. 1 I have shown a power shaft 20 keyed to a bevel gear 22 having an extended hub rotatable in a fixed bearing 23. The driving shaft 16 is alined with the power shaft 20 and the end of the shaft 16 finds a bearing 105 in the hub of the gear 22. The bevel gear 22 meshes with a second bevel gear 24 rotatable in a bearing 25 in the frame 19, and the bevel gear 24 meshes in turn with a third bevel gear 26 loosely mounted upon the 110

driving shaft 16. A sliding clutch collar 27 is keyed to the shaft 16 and suitable devices (not shown) are provided for moving the collar 27 alternately into engagement with the beveled gears 22 and 26, thereby periodically reversing the direction of rotation of the shaft 16. The keyway in the clutch collar 27 is commonly of such width as to allow a substantial amount of lost motion between the collar 27 and the shaft 16 at each reversal of the collar. The parts thus far described form no part of my invention and may be of any usual or desired type.

I will now describe the novel driving connections between the driving shaft 16 and the worm 15. The worm 15 is loosely mounted upon the shaft 16 and is free to move thereon both axially and angularly within certain fixed limits. At its opposite ends the worm is provided with cam disks 30 and 31 which are securely fixed to the worm to rotate therewith. Each disk is provided with a cam surface upon its outer end face, the cam surface 30^a of the disk 30 being positioned to coöperate with a cam roll 32 carried by a driving arm or stud 33 formed upon a sleeve 34, which is fixed to the shaft 16 and is rotatable therewith. In a similar manner the cam surface 31^a of the disk 31 is positioned to coöperate with a cam roll 35 mounted upon a driving arm 36 also fixed to the shaft 16. The relative position of the disks 30 and 31 and the cam rolls 32 and 35 is shown in Fig. 3, the cam roll 32 being shown in driving engagement with a projection 30^b formed at the end of the cam surface 30^a of the disk 30 and thus being effective to rotate the worm 15 in the direction of the arrow *a*. It will be understood that the cam rolls 32 and 35 may upon occasion be omitted, the driving arms then directly engaging the cam surfaces 30^a and 31^a.

Having described the construction of my improved reversing mechanism I will now describe the operation thereof. Taking the parts in the positions shown in Figs. 1 and 3 and moving in the direction of the arrows in said figures, let it be assumed that the direction of rotation of the driving shaft 16 is abruptly reversed. Previous to reversal, the cam roll 32 has been in driving engagement with the projection 30^b upon the cam disk 30, the two disks and the intervening worm being thereby forced to the right until the cam roll 35 engages the cam surface 31^a at the narrowest portion of the disk 31, thereby preventing further movement in that direction. As previously described, the driving connection between the clutch collar 27 and the shaft 16 permits a considerable amount of lost motion between the collar and shaft. During the reversal of the clutch collar and its lost motion relative to the shaft 16, the table, worm wheel and

worm will ordinarily come to rest. In order to prevent relative displacement of the driving arms and their associated cam disks during this idle movement of the parts, I provide the driving arms 33 and 36 with rounded extensions 33^a and 36^a adapted to frictionally engage spring arms 37 and 38 mounted upon the edges of the cams 30 and 31 and each positioned to engage one of the extensions 33^a and 36^a and to thereby hold one of the rolls 32 or 35 in yielding engagement with one of the projections 30^b or 31^b upon the cam disks. Displacement of the parts is thus prevented until the worm and disks begin to revolve positively in the reverse direction. Upon the reversal of the shaft 16, the roll 32 will move away from the front or driving side of the projection 30^b and at the same time the roll 35 will move away from the rear side of a similar projection 31^b upon the disk 31. This relative lost motion of the driving cam-rolls away from the projections 30^b and 31^b permits initial angular movement of the shaft 16 in the reverse direction without causing a corresponding reverse angular movement of the worm 15. As the roll 35 moves away from the rear side of the projection 31^b it engages the long wedge-shaped face 31^a of the cam disk 31 and forces the disks and the intervening worm toward the left (as viewed in Figs. 1 and 3). During this operation the roll 32 is retreating from the cam surface 30^a of the disk 30 and thus interposes no resistance to the axial movement of the disks and worm.

The outline of the cam surface of the disk 31 is shown developed in Fig. 4 and it will be seen that the angle of the cam surface constantly increases toward the high point 105 of the cam, whereby the movement of the worm toward the left will be accelerated. The rate of acceleration may be varied by varying the inclination of the cam face 31^a, and also by varying the speed of revolution 110 of the shaft 16. For example, the rate of angular increase may be so selected that the worm 15 and the table actuated thereby will follow substantially the law of falling bodies in their acceleration. It will be evident that longitudinal movement of the worm 15 will necessarily move the periphery of the wheel 14 in the direction of axial travel of the worm and such movement of the worm wheel will in turn cause corresponding 115 movement of the rack 11 and the table 10. The reverse movement of the table will thus be initiated without shock and with no positive engagement of driving mechanism. As the cam-roll 35 moves to the successive positions shown in dotted lines in Fig. 4 the longitudinal movement of the worm 15 is gradually accelerated, with a corresponding increase in the rate of angular movement of the worm wheel 14. It is my intention to so 120 125 130

proportion the cam surfaces 30^a and 31^a of the disks 30 and 31 that the worm wheel 14 shall be moving at substantially its normal rate of rotation at the moment when the 5 cam roll 35 engages the driving side of the projection 31^b upon the cam disk 31. The worm will thereafter be revolved by the cam roll 35 as if it were rigidly secured to the shaft 16. As the worm wheel and table are 10 already moving at their normal speed when the transition is made from axial to angular driving movement of the worm 15, there will be no change in velocity of table travel at this moment and therefore no unusual 15 strains will be thrown upon the mechanism. The worm wheel and table have been started from rest and brought up to their normal speed by a gradual acceleration and the force necessary to cause such acceleration 20 has been permitted to act over the entire available time interval.

It will be noted that the attainment of normal speed at the moment of positive driving engagement depends solely upon the 25 inclination of the cam face 30^a or 31^a, and that it does not depend upon the speed of rotation of the cams. It follows that the cam surfaces, when properly proportioned for one speed in a given driving combination, are correct for all other speeds of the 30 same combination, without alteration or adjustment. It may sometimes be desirable to allow a longer interval in which the table may be brought to rest. Under these conditions, I provide cam disks 40 as shown in Fig. 5, in which the portion 40^a of the cam surface slopes toward the left, as viewed in said figure, while the portion 40^b slopes toward the right as in the cam shown in 35 Fig. 4. With this construction the table may continue its movement in the direction of previous travel for a short distance after the worm and disks have commenced their reverse rotation. After the cam roll reaches 40 the low point of the cam, the table is gradually set in motion in the opposite direction, as previously described. Lost motion between the collar 27 and shaft 16 is unnecessary with this form of cam. The same result 45 may also be attained by the use of the construction shown in Fig. 6 in which the driving arms 330 and 360 are fixed at the opposite ends of a sleeve 50 keyed to the driving shaft 160 and slidable thereon between shoulders 51 and 52. The shaft 160 is 50 mounted in bearings 170 and 180 as previously described, whereby endwise movement of the shaft is controlled. If the parts are moving in the directions shown in Fig. 1, the pressure of the worm against the worm wheel will force the sleeve 50 against the shoulder 51. When forward rotation of the worm ceases, slight continued rotation of the worm wheel due to the inertia of the 55 table will slide the worm and sleeve along

the shaft 160 until the sleeve engages the shoulder 52, against which it will be held by the pressure of the worm when driving in the reverse direction. The distance through which the sleeve is permitted to 70 slide upon the shaft 160 may be suitably related to the special conditions arising in any given machine. For the purposes of the claims it is to be considered immaterial whether the driving arms engage the disks 75 directly or through the medium of the cam rolls.

Having thus described my invention it will be evident that other changes and modifications can be made therein by those skilled in the art without departing from the spirit and scope thereof as set forth in the claims, and I do not wish to be otherwise limited to the details herein described, but

What I claim is:—

1. A reversing mechanism having, in combination, a driving shaft, means for rotating said shaft alternately in opposite directions, a worm mounted on said shaft, a worm wheel meshing with said worm, and driving connections between said shaft and worm effective to move said worm wheel after reversal at a gradually accelerating speed and to thereafter drive said worm wheel positively at normal speed.

2. A reversing mechanism having, in combination, a driving shaft, means for rotating said shaft alternately in opposite directions, a worm mounted on said shaft, a worm wheel meshing with said worm, and driving connections between said shaft and worm effective to move said worm wheel after reversal at a gradually accelerating speed until substantially normal speed is attained and to thereafter drive said worm wheel positively at normal speed.

3. A reversing mechanism having, in combination, a driving shaft, means for rotating said shaft alternately in opposite directions, a worm mounted on said shaft and movable both angularly and axially relatively to said shaft, a worm wheel meshing with said worm, and means to give said worm, upon reversal of said shaft, an initial axial movement of gradually increasing velocity followed by a positive movement of rotation with said driving shaft.

4. A reversing mechanism having, in combination, a driving shaft, means for rotating said shaft alternately in opposite directions, a worm mounted on said shaft and movable both angularly and axially relatively to said shaft, a worm wheel meshing with said worm, means to move said worm bodily endwise upon reversal of said shaft, thereby imparting a movement of rotation in the reverse direction to said worm wheel, and means to positively rotate said worm when the movement of said worm wheel approximates its normal speed of rotation.

- 4
5. A reversing mechanism having, in combination, a driving shaft, means for rotating said shaft alternately in opposite directions, a worm mounted on said shaft and movable both angularly and axially relatively to said shaft, a worm wheel meshing with said worm, and driving connections between said shaft and said worm, said connections including a cam and a driving arm at each end 10 of said worm effective to give said worm a limited movement both axially and angularly relatively to said shaft at each reversal thereof.
6. A reversing mechanism having, in combination, a driving shaft, means for rotating said shaft alternately in opposite directions, a worm mounted on said shaft and movable both angularly and axially relatively to said shaft, a worm wheel meshing with said worm, and driving connections between said shaft and said worm, said connections comprising reversibly-disposed cam disks secured to the opposite ends of said worm and a pair of driving arms fixed to said shaft 20 and each positioned to coöperate with one of said cam disks for driving said worm.
7. A reversing mechanism having, in combination, a driving shaft, means for rotating said shaft alternately in opposite directions, a worm mounted on said shaft and movable both angularly and axially relatively to said shaft, a worm wheel meshing with said worm, and driving connections between said shaft and said worm, said connections comprising reversibly-disposed cam disks secured to the opposite ends of said worm, and a pair of driving arms fixed to said shaft in spaced relation thereon and each positioned to coöperate with one of said disks to drive 30 said worm in one direction.
8. A reversing mechanism having, in combination, a driving shaft, means for rotating said shaft alternately in opposite directions, a worm mounted on said shaft and movable both angularly and axially relatively to said shaft, a worm wheel meshing with said worm, and driving connections between said shaft and said worm effective to rotate said worm wheel by direct axial movement of said worm at the beginning of each reverse 40 movement of said worm wheel and to thereafter continue said rotation in the same direction by rotation of said worm.
9. A reversing mechanism having, in combination, a driving shaft, means for rotating said shaft alternately in opposite directions, a worm mounted on said shaft and movable both angularly and axially relatively to said shaft, a worm wheel meshing with said worm, driving connections between said shaft and said worm, said connections including a cam and a driving arm at each end of said worm effective to give said worm a limited movement both axially and angularly relatively to said shaft at each reversal thereof, and means to retain said cams and driving arms yieldingly in driving engagement.
10. A reversing mechanism having, in combination, a driving shaft, means for rotating said shaft alternately in opposite directions, a sleeve rotatable with said shaft and slidable between fixed shoulders thereon, a worm mounted on said sleeve and movable both angularly and axially relatively to said sleeve, a worm wheel meshing with said worm, and driving connections between said sleeve and said worm, said connections comprising reversibly-disposed cam disks secured to the opposite ends of said worm and a pair of driving arms fixed to said sleeve in spaced relation thereon and each positioned to coöperate with one of said disks to drive 50 said worm in one direction.

In testimony whereof I have hereunto set my hand.

CHARLES H. NORTON.
